SELDON L. CROCKETT AND BENJAMIN T. MILLS, OF LOWELL, MASSACHUSETTS, ASSIGNORS TO BENJAMIN T. MILLS, OF THE SAME PLACE.

Letters Patent No. 76,895, dated April 21, 1868.

IMPROVEMENT IN CAM FOR CARD-STRIPPING MACHINE.

The Schedule referred to in these Letters Patent and making part of the same.

TO ALL WHOM IT MAY CONCERN:

Be it known that we, SELDON L. CROCKETT and BENJAMIN T. MILLS, both of Lowell, in the county of Middlesex, and State of Massachusetts, have invented certain new and useful Improvements in Machinery for Stripping the Top-Flats of Carding-Engines, of which the following is a full, clear, and exact description, reference being had to the accompanying drawings, making part of this specification, in which—

Figure 1 represents an end elevation of a portion of a carding-engine, showing the stripper-arm A, with the lifting, depressing, and replacing-cam B in its proper position for the easy and gradual lowering or replacing of one of the top-flats C, or for being turned backward to carry the stripping-devices over to a point out of the way of the back side of the engine, so that the operator may get at the main cylinder, to strip the same.

Figure 2 represents a portion of the back side of the carding-engine, showing an edge view of the stripper-arm A, cam B, and the slide m and jaw n, with the upper pin 1, outside of the outer flange k, as also seen in fig. 1.

Figure 3 represents the back or working side of one of our improved cams, full size for practice, but with an outer flange, k', not shown in fig. 1.

Figure 4 represents a central section of fig. 3, on the line A B thereof.

Figure 5 represents the back or working side of the cam B, shown in fig. 1.

In this invention, the stripper-arm A, and the lifting, depressing, and replacing-cam B, are arranged, in relation to the carding-engine, in about the same manner as in the ordinary stripping or cleansing-machinery; but the construction of the cam B, and the manner of operating the slide m and the jaw n to lift, depress, and replace the top-flats, by means of the pins 1, 2, and 3, are altogether different from ordinary top-flat stripping-machinery in the following particulars:

In the ordinary top-flat stripping-machinery, the top-flats are depressed on to the strip-card by means of a spring, or by the pin projecting from the slide, or a thimble on said pin, filling the groove between two flanches, the curves of which are regular, as from 10 to 10 in fig. 3, except a depressing bulge, 12, and an opposite depression, 13. In the stripping-device patented by George Wellman, the top-flat is depressed by a spring secured to the under side thereof. The depressing-pin (being the next to the inner one) is held in contact with the outside of one of the lifting-flanches, which has an offset formed therein, to lower the pin, and hence the elevated top-flat, on to the strip-card, said elevated top-flat being pressed down by the spring above named. In the stripping-device patented by us, October 23, 1866, the offsets or irregular curves 12 and 13, shown in fig. 3 of this invention, are provided, and the pin or thimble 2 of the said patent fills the groove P there shown, and thereby produces a positive depression of the top-flat, as therein set forth and shown.

We find it very important, while the top-flat is being cleaned, to save the teeth at the front side of the strip-card or the strip-board, and at the back side or edge of the top-flat, from being injured when said strip-board is receding or being withdrawn from beneath the elevated top-flat. In all the stripping-devices previously patented, the top-flats drag on the strip-card all the way out from beneath said top-flats. This dragging action, with the depressing-springs acting on the top-flat, so breaks down and injures the card-teeth on the front side or edge of the strip-board, and at the back side of each top-flat, that the card-clothing on the strip-board, and also on the top-flats, has to be removed quite often and replaced by new.

To obviate this difficulty, and save the card-teeth above referred to, we construct the outer portion of flanch E as shown, and, when the cam rotates, the pin 3 passes into the groove F, between the flanges E and G, and upward over the rounded projection 5, and in its passage from 5 to 6, the strip-card is passing under the elevated top-flat. After the pin 3 has passed the point 6, it moves gradually downward in the depression between 6 and 7, remaining in that position, with the top-flat bearing on the strip-card while the pin passes from 6 to 7, which allows the strip-card sufficient time to take the waste substance on the top-flat, and to remove it from beneath said flat. Just before the strip-card leaves the top-flat, the pin 3 rises on the bulge 7, and moves the

top-flat upward slightly, but enough to relieve the pressure of the top-flat on the strip-card, and prevent any injury to the card-teeth on the front edge of the strip-card and the back edge of the top-flat.

Here it will be seen, that when the bulge 7 on the flanch E of the rotating cam passes under the pin 3, projecting from the slide, the top-flat, which is already elevated, receives another upward movement, imparted by the bulge 7, which not only raises the elevated top-flat, but holds it up until the strip-card has been fully withdrawn from beneath it.

This raising and holding up of the top-flat at each operation of stripping a top-flat, and at a time immediately preceding the full withdrawal of the strip-card from beneath each elevated top-flat, relieves the crushing or pressing and dragging action of the card-teeth on the front edge of the strip-card and on the back edge of each top-flat, and saves the card-teeth, at each extremity above named, from being bent or injured when the strip-card is withdrawn from beneath each elevated top-flat.

Each operation of stripping and relieving is performed in succession on every top-flat in the whole series.

Another important feature in this invention is working the upper pin 1 on the outside of the outer flanch, as shown clearly in the drawings. And if the flanch k', shown in fig. 3, is the outer flanch, then a fourth pin, 4, may be employed above the pin 1, and in either case, such outer or upper pin is operated by such outer flanch, to ease the top-flats down; and if a flanch is arranged on the cam B, to thus gradually, evenly, slowly, and carefully ease the top-flats down, after being stripped or cleansed, such a cam may at any time be turned backward to move the stripping-device therewith connected over to the front side of the carding-engine, so that the operator may get at the main cylinder to strip the same. Other flanches may be added to the cam B, and other pins to the slide m, to the extent of their dimensions. In all cases the top-flat is eased down, after being stripped or cleaned, with the upper pin on the outer flanch and on the outer surface of said flanch.

Some portions of the outer flanch, which eases down the top-flats, may be detached, as the portion L of the flanch k' of fig. 3, or the portion L of the outer flanch k in the cam B in fig. 1; but we consider a continuous flanch much the best, and preferable to broken or detached flanches, as there is no liability of the pins getting between two detached portions, and continuous flanches are so much stronger, that there is no liability of their being broken by ordinary use or wear.

The portions or ends a, a¹, and a² of the flanches, and which raise the pins 1, 2, 3, or more, are not so essential, but the portions or ends a³ and a⁴ of such flanches are of the utmost importance in lowering or easing down the top-flats, as above stated.

By the use of a cam constructed as shown and described, a greater elevation of the top-flat may be had with a cam of a given diameter, than by a cam of any other construction, and the top-flats can be lowered or replaced in much less time than by any other known device.

The object in replacing the top-flats speedily after being cleaned is to prevent waste and dust, from the rapidly-revolving card-cylinder, being expelled from the opening left by the elevated top-flat, into the room, to annoy the operators.

We have stated that an important feature in this invention is working the upper pin 1 on the outside of the outer flange. We have also stated, that by the use of a cam, constructed as shown and described, a greater elevation of the top-flat may be had, with a cam of a given diameter, than by a cam of any other construction.

In the use of flanged cams, operating upon pins projecting from the slides for elevating and replacing the top-flats of carding-engines, the flanges of such cams are frequently broken, which renders it necessary that the broken cam should be removed, and a perfect cam put on to the stud or axis in place of a broken one.

These lifting and replacing-cams are applied to a stud or axis secured to and projecting from some part of the movable frame which carries the stripping-apparatus, and at one end of the carding-engine the cam is a short distance inside of the driving-pulleys. The inside or tight or fast pulley is firmly secured to the central shaft by a spine or key, and is difficult to be removed; and therefore it is very important that these cams should be so small in diameter that the cam on the driving-end of the carding-engine may be removed, when broken or injured, and a perfect cam put on in its place without removing the driving-pulley. It is quite important that these lifting and replacing-cams should have flanges so formed and arranged that, by the use of a suitable number of operating-pins, projecting from each slide, a cam of small diameter will operate the slides, and move each successive top-flat from its lowest to its highest position, and back again, without undue strain or pressure on the flanges, to break them, and without the aid of springs or other auxiliary devices, which only complicate the carding-engine, render it more expensive and troublesome to keep in working condition, and increase the liability to get out of order.

We have found, by experiment, that the greater the number of flanges on the face of the cam-plate, and a suitable or corresponding number of pins projecting from the slide, the easier the operation of all the parts connected, and the greater the reduction of friction, and of breaking-pressure on the cam-flanges and on the pins of the slide, as each flange and each pin perform but a small part of the whole operation.

To insure and maintain this easy and safe operation of the cam and the pins, and to provide for the easy, safe, and sure reversing of the motion or the direction of rotation of the cam, so that the operator can turn it back, and get at the main cylinder, to strip it, at any time, we have found that, by operating the outer or upper pin (be there two, three, or more pins) on the outer edge of the outer flange, all the other flanges and all the other pins are greatly relieved during such turning-back operation, and that the liability of breaking the flanges and the pins is so greatly diminished that, in all these, our numerous cams, now in operation, not a single cam-flange or a pin has ever been broken, or a part injured, beyond that occasioned by ordinary wear, which we consider the best of evidence in favor of our improved method of operating the slide, both in the regular forward movements of the stripping-apparatus, and in reversing the motion or the direction of rotation of the cam, to turn the stripping-apparatus back, for the purpose described.

Previous to our experiments, it has always been supposed that an operating-flanch, outside of the outer or upper pin in the slide, was necessary to control the action of the slide; and such an outer flanch is seen on all card-stripping cams patented previous to this application; but we have found, by experiment, that a cam can be constructed for the purpose described, without any outer flanch beyond the outer or upper pin in the slide, and that, by the use of such a cam, and by operating the upper or outer pin on the outer edge, or the outer extremity of such outer flanch, the action of all the pins on all the flanches, or the force, strain, and motion of the operating parts can be better and more equally distributed, and thus prevent the breaking and unnecessary wear of the cam-flanches and the pins, and greatly economize, not only in the removal and the replacing of cams, but in the first and in all future costs and expenses attending their application and use.

We are therefore very sure that, by operating the pin 1, or the upper or outer pin, on the outer edge or portion of the outer flange *k*, as described, the cam, pin, and slide are easier operated; the friction in or upon the operating parts is greatly reduced; considerable power is saved by the reduction of friction, and the consequent easy action; that the costs and expenses attending the application and use of such devices will be considerably lessened, and that all the operating parts connected will be rendered serviceable for a much longer time, and much less liable to break or wear, or be otherwise injured.

What we claim as new, and desire to secure by Letters Patent, is—

1. We claim the lifting and replacing-cam B, constructed as shown and described, viz, with the prominent portions indicated as 5, 6, and 7, and the depression between 6 and 7, and a flanch or flanches, *k*, to relieve and ease down the top-flats, and again elevate the same, substantially in the manner and for the purpose set forth.

2. We claim the cam B, provided with a flange, *k*, constructed as described, and operating in connection with the slide and its pin 1, as and for the purpose set forth.

SELDON L. CROCKETT,
BENJAMIN T. MILLS.
